CLAIM

We claim the ornamental design for a light fixture, as shown and described.

DESCRIPTION

FIG. 1 is a perspective view of a light fixture according our new design.

FIG. 2 is a perspective view of the light fixture shown in FIG. 1.

FIG. 3 is a first side view of the light fixture shown in FIG. 1.

FIG. 4 is a second side view of the light fixture shown in FIG. 1.

FIG. 5 is a first plan view of the light fixture shown in FIG. 1.

FIG. 6 is a second plan view of the light fixture shown in FIG. 1; and,

FIG. 7 is an end view of the light fixture shown in FIG. 1. The elements shown in broken lines are included for the purpose of illustrating portions of the article that form no part of the claimed design.

1 Claim, 3 Drawing Sheets
